CLAIM

The ornamental design for a water leak sensor, as shown and described.

DESCRIPTION

FIG. 1 is a front perspective view of a water leak sensor showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines shown in the drawings are for the purpose of illustrating portions of the article, and form no part of the claimed design.
